UNITED STATES PATENT OFFICE.

WILLIAM C. BROWN, OF BRIDGEPORT, CONNECTICUT.

DESIGN FOR A TRADING-STAMP.

SPECIFICATION forming part of **Design No. 28,784**, dated June 7, 1898.

Application filed April 27, 1898. Serial No. 679,042. Term of patent 3½ years.

To all whom it may concern:

Be it known that I, WILLIAM C. BROWN, a citizen of the United States, residing at Bridgeport, in the county of Fairfield and State of Connecticut, have invented and produced a new and original Design for Trading-Stamp; and I do hereby declare the following to be a full, clear, and exact description of the invention, such as will enable others skilled in the art to which it appertains to make and use the same.

The accompanying drawing represents in elevation my new design.

The essential features of my design comprise the rectangular body provided with the

plain circular figure 1 and the plain triangular figure 2 imposed thereon, which latter by one of its apices intersects said circular figure in such manner that the intersecting apex of the triangle appears within and is inclosed by the inner circular boundary of said figure 1.

I claim—

The design for a trading-stamp, substantially as shown in the accompanying drawing.

In testimony whereof I affix my signature in presence of two witnesses.

WILLIAM C. BROWN.
